UNITED STATES PATENT OFFICE.

EWALD W. WEYRAUCH, OF ROCHESTER, NEW YORK.

RACK FOR TALKING-MACHINE RECORDS.

Application filed January 31, 1921. Serial No. 441,186.

To all whom it may concern:

Be it known that I, EWALD W. WEYRAUCH, a citizen of the United States, and resident of Rochester, in the county of Monroe and State of New York, have invented certain new and useful Improvements in Racks for Talking-Machine Records, of which the following is a specification.

The present invention relates to racks for talking machine records and an object thereof is to provide an inexpensive construction which is strong and durable in use and may be inserted within the usual cabinet of a talking machine and expanded or contracted to accommodate any desired number of records of any size.

To this and other ends the invention consists of certain parts and combinations of parts, all of which will be hereinafter described, the novel features being pointed out in the appended claims.

In the drawings:

Fig. 1 is a fragmentary front view of a rack constructed in accordance with this invention;

Fig. 2 shows in side elevation on a reduced scale, a modification of the partitions;

Fig. 3 shows in side elevation on a reduced scale another modification of the partitions;

Fig. 4 is a vertical section on the line 4—4, Fig. 1;

Fig. 5 is a detail view of one of the tie-rod sections;

Fig. 6 is a detail sectional view of one end of the tie-rod;

Fig. 7 is a detail section of the opposite end of the tie-rod;

Fig. 8 is a fragmentary view showing the manner in which the record rests upon one of the supporting and displacing levers; and

Fig. 9 is an enlarged section on the line 9—9, Fig. 4, of one of the partitions.

The rack embodies a number of partitions, each of which preferably is formed by a thin sheet of cardboard or other material reinforced at all of its edges except the lower edge by a metal strip 2, which is bent on opposite sides of the sheet portion 1. The form of the sheet portion 1 may be varied from that shown in Figs. 1 and 4, as for instance, as shown in Figs. 2 and 3 at 1^a and 1^b respectively, in which case the metal reinforcing strips 2 conform to the edges of the sheet.

The partitions are held together by a number of tie-rods which, in this instance,

are in sectional form, each section 3 preferably having a screw threaded extension 4 at one end, and a socket 5 at the opposite end, the walls of which are internally threaded to receive an extension on an adjacent section. The length of these sections is immaterial as they may all be the same length or of different lengths. Detachable abutment pieces 6 and 7 are provided at opposite ends of each tie-rod, the abutment piece 6 having a screw threaded projection 8 adapted to fit in a socket 5, while the abutment piece 7 has a screw threaded opening adapted to fit upon an extension 4, a collar 9 preferably also surrounding said extension between the nut or collar 7 and the inner end of the screw 4. Surrounding the tie-rods 3 is a number of collars 10 which act to space the partitions from each other.

Connecting the forward reinforcing pieces 2 of the partitions is a sectional pivot rod 11, the sections of which are connected like the sections of the tie-rod. On this pivot rod 11, the supporting and displacing levers 12 are pivoted. These supporting and displacing levers, in this instance, are each formed from a sheet metal strip bent longitudinally into U shape in cross section, the edge being disposed downwardly and the top surface 85 preferably being provided with a longitudinally extending groove 13. The width of each lever is substantially equal to the distance between the reinforcing pieces of two adjacent portions so that the lever is confined against movement in the direction of its axis. The rear end of each lever preferably rests upon the spacing collars 10 on the tie-pieces 3 to be supported by the latter.

The rear reinforcing pieces 2 have a sectional rod 14 extending therethrough above the rear ends of the supporting and displacing levers 12, and the records 15, when resting upon the levers while the latter rest upon the collars 10, lie in abutment with this abutment 14 as shown in dotted lines in Fig. 4.

To insert the records in the cabinet, they are introduced between the partitions and roll to the rear on the levers 12 until the abutment rod 14 is reached, thus permitting disks of any diameter to be received within the cabinet. To displace the disks, the forward ends of the levers 12 are depressed and the records roll forwardly to be received in the hand of the operator.

From the foregoing it will be seen that

there has been provided a record rack which may be inexpensively manufactured, is durable in use, and may be received within a compartment of the ordinary talking machine cabinet. This rack may be contracted or expanded to accommodate any desired number of records of any size. The partitions are of novel construction and are connected together by sectional tie-rods which, in this instance, permit the expansion and contraction of the rack. One of the tie-rods serves as a rest for the rear ends of the operating levers which are pivoted on a sectional rod extending through the forward reinforcing pieces at the front edges of the partitions.

What I claim as my invention and desire to secure by Letters Patent is:

1. A rack for talking machines comprising partitions, tie-rods connecting said partitions, two of said tie-rods being situated near the lower edges of the partitions, one being near the front edge and the other being near the rear edge, levers pivoted be-

tween the partitions on a common pivot situated adjacent the front edge above the tie-rod near such edge, said levers having their upper surfaces straight and extending in an inclined position from their pivots rearwardly to rest on the tie-rod near their rear edge, and an abutment extending through said partitions above but in front of the rear end of the ends of the levers, and, at the same time, forming stops for the records to limit the movement of the latter rearwardly on the levers.

2. A rack for talking machine records comprising partitions having reinforcing strips at their front and rear edges, tie-rods extending through said reinforcing strips and connecting said partitions, a pivot rod extending through the forward reinforcing strips, and levers pivotally mounted on said rod and having their rear ends supported by a tie-rod extending through the rear reinforcing strips.

EWALD W. WEYRAUCH.
